DESIGN FOR A PROJECTOR

John R. Miles, Rochester, N. Y., assignor to
Bausch & Lomb Optical Company, Rochester,
N. Y., a corporation of New York

Application August 21, 1936, Serial No. 64,501

Term of patent 7 years

To all whom it may concern:

Be it known that I, John R. Miles, a citizen of the United States and a resident of Rochester, county of Monroe, and State of New York, have invented a new, original, and ornamental Design for a Projector, of which the following is a specification, reference being had to the accompanying drawing, forming a part hereof.

Fig. 1 is a front perspective view of a projector, showing my new design.

Fig. 2 is a rear perspective view of same.

I claim:

The ornamental design for a projector, substantially as shown.

JOHN R. MILES.
